UNITED STATES PATENT OFFICE.

CHARLES D. TILLISON, OF ST. LOUIS, MISSOURI.

SMOKE-CONDUCTOR.

SPECIFICATION forming part of Letters Patent No. 453,379, dated June 2, 1891.

Application filed March 23, 1891. Serial No. 386,092. (No model.)

To all whom it may concern:

Be it known that I, CHARLES D. TILLISON, of the city of St. Louis, State of Missouri, have invented certain new and useful Improvements in Smoke and Cinder Conveyers for Railway-Cars, of which the following is a full, clear, and exact description, reference being had to the accompanying drawings, forming a part hereof.

10 My invention relates to improvements in smoke and cinder conveyers for railway-cars; and it consists in the novel arrangement and combination of parts, as will be more fully hereinafter described, and designated in the 15 claims.

In the drawings, Figure 1 is a longitudinal sectional view of my invention as applied functionally to railway-cars. Fig. 2 is a top plan view of the same. Fig. 3 is an end view 20 of a car, showing my invention applied to the same; and Fig. 4 is a detail view showing the manner in which part of my invention is applied to the smoke-stack.

The object of my invention is to construct 25 a device for preventing the products of combustion—such as smoke, cinders, soot, &c.—issuing from the smoke-stack of the locomotive from entering the doors or windows of the moving train.

30 While embodying this essential feature, I desire to so construct my device that it is easily detachable from the smoke-stack, and it is not necessary to change, essentially, the location of the parts of my invention when 35 the train moves in opposite direction. It can also be readily perceived that by the peculiar construction of the pipes of the conveyer where the same join they are adapted to gather air and create a draft through the conveyer, and consequently remove effectually 40 all the products of combustion that may enter the conveyer.

Referring to the drawings, 1 indicates a 45 smoke-stack of ordinary construction as carried by an ordinary locomotive, and 2 indicates the top of the cab of the same.

3 indicates an approximately S-shaped joint, with a front portion of the same flared divergently, the same adapted to fit snugly 50 over the top of the smoke-stack.

Any suitable mechanical construction may be employed that will create a perfect joint

where the S-shaped joint and smoke-stack meet, so that no products of combustion can escape at the joint. Said S-shaped joint 3 is 55 adapted to be removed from the smoke-stack from the cab in a manner as will be more fully hereinafter described. Of course this construction is absolutely necessary, for when the locomotive is standing still there is no 60 need of the conveyer being placed over the smoke-stack of the same.

4 indicates a stationary pipe, which is firmly secured to the top 2 of the cab in any suitable and mechanical manner. The front portion of said pipe is provided with a funnel-shaped portion 5, in which the end of the S-shaped joint 3 is adapted to slip. The rear end of the S-shaped joint 3 is of smaller diameter than the funnel-shaped portion 5 of 70 pipe 4, so that when pipe 3 is placed in said funnel-shaped portion there is sufficient space for the air to enter, as indicated by arrow 6, thereby creating a draft through the pipe 4. Pipe 3 is provided with a perforated lug 7, to 75 which is pivotally secured a lever 8.

9 indicates a band which is secured to smoke-stack 1 in any suitable and mechanical manner. Said band is provided with a perforated arm 10, to which lever 8 is pivotally 80 secured. The lower arm 11 of lever 8 is pivotally secured to an operating-handle 12, which passes back and is adapted to be operated from the cab. By this construction it can be readily perceived that when the operating-handle 12 is pushed forward the S-shaped pipe or joint 3 will be removed from its seat on smoke-stack 1 and pushed backward into the funnel-shaped portion 5, thereby throwing the smoke-stack in communication 90 with the open air. Of course when it is desired to place the S-shaped joint on the smoke-stack the operation should be reversed—that is, the operator should pull handle 12 toward 95 him.

13 indicates a straight pipe, which is adapted to slip over pipe 4 in a forward direction or to slip backward in a funnel-shaped portion 14 of the pipe 15, or, if necessary, pipe 13 can be slipped backward in pipe 15, so as 100 to remove pipe 13 out of the way when it is desired to supply the tender 16 with water at the water-tank. The funnel-shaped portion 14 has two functions: First, it allows the pipe

13 to vibrate freely on an uneven track and around curves, and, second, it will gather sufficient air to create a draft and force all the products of combustion back to the next pipe 5 on the rear car, where a like construction is employed, and of course a like result follows.

Each car of the train should be provided with a like pipe, as 15, and put together as the construction shown in locating the pipes 10 13 and 15. The pipes are secured in any suitable and mechanical manner on the roofs of the cars adjacent to the sides of the raised portion of the roofs, as shown in Fig. 3.

In order to prevent changing the pipes when 15 the train moves in an opposite direction, I use a similar set of pipes, but having the funnel portions of the same in a reverse position to that as shown in Fig. 1 and as shown in Fig. 2; but in order to bring pipe 4 in the two 20 mentioned constructions in a proper location relative to the S-shaped joint 3 I bend the pipe as shown in Fig. 2.

25 indicates a forked or bifurcated guide, which is secured to the smoke-stack in any suitable and mechanical manner. The joint 3 occupies an interposed position between the forks or bifurcations of said guide. The function of said guide is to guide joint 3 and prevent it from tilting laterally when same is desired to be placed on or moved from the smoke-stack.

Having fully described my invention, what I claim is—

1. In a smoke and cinder conveyer for rail- 35 way-cars, the combination, with pipe-sections which are located on the cars, of a section 4, located on the locomotive, means for con-

necting the latter section with the smoke-stack, and a section 13, removably and adjustably carried by supports upon the tender, the 40 said section 13 being adapted to fit over the end of section 4 and to be slid into and contained within one of the sections on the cars when the tender is being filled, substantially as described.

45 2. In a smoke and cinder conveyer for rail-way-trains, a pipe carried by the cars, a short pipe 3, one end of which is adapted to fit into the end of said first-mentioned pipe, the opposite end fitting over the top of the smoke- 50 stack, guides 25, lying in the same plane as the upper edge of said stack, and means whereby the short pipe 3 may be operated on said guides to connect or disconnect the stack train-pipe, substantially as described.

55 3. In a smoke and cinder conveyer for rail-way-trains, a pipe carried by the cars, a short pipe 3, one end of which is adapted to fit into the end of said first-mentioned pipe, the opposite end being placed and fitting over the top of the smoke-stack, guides 25 at the top of said stack, a lug 7 on pipe 3, a lever 8, pivoted thereto, a band 9, carrying an arm 10, secured to the stack, the lever 8 being pivoted to arm 10, and an operating-rod 12, connected 60 to the lower end of said lever, substantially as described.

65 In testimony whereof I affix my signature in presence of two witnesses.

CHARLES D. TILLISON.
